TRACK FOR MINIATURE ELECTRIC TRAINS

Filed Nov. 22, 1927

Patented Aug. 14, 1928.

1,680,918

UNITED STATES PATENT OFFICE.

WALTER E. THAYER, OF LOCKPORT, NEW YORK.

TRACK FOR MINIATURE ELECTRIC TRAINS.

Application filed November 22, 1927. Serial No. 235,004.

This invention relates to toy railway tracks, that is tracks for miniature electric trains, and the general object is to provide an improved track section for such trains which may be readily assembled and readily engaged with other track sections.

A further object is to provide improved means for fastening the rails of the tracks to the ties.

10 A still further object is to provide a middle rail and provide improved means for holding the middle rail in place, the middle rail at its ends being free to move to a slight extent so that the middle rail may be engaged with the middle rails of other track sections where the middle rail is higher than in the track section which I have devised.

20 Another object is to provide an improved metallic connection or conductor between the outer rails for insuring better flow of the electric current, and to provide means whereby electric terminal wires may be connected to the rails.

25 Other objects will appear in the course of the following description.

My invention is illustrated in the accompanying drawing, wherein:—

Figure 1 is a top plan view of a track constructed in accordance with my invention;

30 Figure 2 is a cross section on the line 2—2 of Figure 1;

Figure 3 is a section on the line 3—3 of Figure 1;

35 Figure 4 is a side elevation of one end of the track, the tie at this end being in section.

Referring to this drawing, 10 designates the wooden ties of the track section and 11 the rails. These rails are made of thin metal and are bent so as to form a bead which constitutes a head 12 and the two parallel webs 13. The ties 10 are transversely slotted, as at 14, for the reception of the web 13 and the rails are held upon the ties by transverse pins 15 extending longitudinally through the ends of each tie and through the webs of the outer rails. The tie may be initially bored for the reception of this pin or the pin may be driven longitudinally through the tie.

It is to be noted that the middle slot 14 is not as deeply cut as the slots on each side thereof so that the middle rail is higher than the two lateral rails. This is for the purpose of joining this particular track section with other makes of track section which

have the center rail higher due to their peculiar construction. The middle rail of each section of track is held to the ties intermediate its ends by nails or pins 16, as shown in Figure 1, driven diagonally downward through the web 13 of the rail, and into the tie. Preferably each rail section has a tie at each extremity and the middle rails are unattached to these end ties, thus permitting the middle rail at its ends to be adjusted vertically or be free to adjust themselves to other makes of track which may vary in the height of their middle rails. The middle rail and either one of the side rails may be apertured at 17 for the purpose of attaching electric terminal wires, such connections being made by bolts or spring devices which form no part of my present invention. Metallic conducting members, preferably of copper and designated 18, are disposed at intervals to electrically connect the outer rails to each other. Each conductor 18 is formed of a flat strip of copper having its ends bent upward, as at 19.

The tie is formed upon its under face with recesses 20 which intersect the kerfs 14. The ends 19 are extended upward through these recesses 20 and into the kerfs 14 and when the rail is put in place the web of the rail 13 will bear tightly against and have a close electrical connection with the ends 19. The extremities of these angularly bent portions 19 are clenched by means of a punch which strikes these bent over extremities 21 and forces them down into the wood, this punch at the same time making a recess into which the extremities are forced. Thus this metallic conductor is clenched in place and cannot get out of place and constitutes a good bond between the outer rails.

While I have illustrated and described straight sections of track having my improvements applied thereto, it will be understood that these improvements might be applied to curved sections containing perhaps more ties than straight sections, to switches either mechanically or electrically operated, to crossovers, sidings, etc. Preferably the rails will be made of rust-proof metal and the connections will be made of copper. Thus the tracks may be used out of doors. The rails are made in such a manner as to make the sections of track stiff and at the same time prevent injury to the fingers of a child assembling or disassembling the track. The rails and ties may be made as

separate units so that the child can construct his own track or the rails and tracks may be assembled and thus sold in sections. Preferably the bead 12 constituting the head of

5 the rail will have therein at one end copper pins or terminal connections 23, these copper pins on one section extending into the beads constituting the heads 12 on the other section of the track.

10 I claim:—

1. In a miniature railway, ties having transversely extending kerfs, and a rail having a web extending down into said kerfs and a pin extending through one end of each 15 tie and through the web of the rail.

2. In a miniature railway, a tie having a transverse kerf, a rail of thin sheet metal formed to provide a hollow bead constituting the head of the rail, and parallel portions 20 constituting the web of the rail, the web being inserted within the kerf, and a pin extending through the end of the tie and through the web of the rail and holding the latter in place.

25 3. In a miniature track, a plurality of ties, each tie having three transverse kerfs, the lateral kerfs extending below the level of the middle kerf, rails each having a web insertible into said kerfs, the middle rail being above the lateral rails, means locking the lateral rails in place upon the tie, and independent means for locking the middle rail upon certain of the ties.

4. In a miniature electric railway track, 35 ties having transverse kerfs, metallic rails having webs inserted in said kerfs, and bonding connections connecting said rails, each connection comprising a strip of copper extending along the bottom of a tie and having its ends extended upward into metallic

contact with the rails and the extremities of said upwardly extending ends being clenched upon the tie.

5. In a miniature railway, ties having transverse kerfs, metallic rails having webs 45 inserted in said kerfs, certain of the ties having recesses extending upward from the bottom of the tie and intersecting said kerfs, metallic strips disposed against the bottom of the tie and having upwardly extending 50 end portions inserted through said recesses into the kerfs and having tight electrical connection with the webs of the rails, the extremities of said upwardly extended portions being clenched downward into the tie. 55

6. In a track section for miniature electric railways, ties, each having three transverse kerfs, a middle rail and two lateral rails having webs formed to engage in said kerfs, the middle rail being connected to the ties 60 intermediate its ends and the ends of the middle rail being vertically movable with relation to the ties whereby the ends may be adjusted into alignment with the ends of adjacent middle rails. 65

7. In a track section for miniature electric railways, a rail having a web, ties for the ends of the rails and the intermediate portions of the rail, each tie having a kerf within which the web is inserted whereby the 70 rail is held from lateral movement relative to the ties, and means connecting the rail to the ties intermediate the ends of the rails whereby the ends of the rails may be vertically moved with relation to the corresponding tie without detaching the web from the kerfs of the end ties. 75

In testimony whereof I hereunto affix my signature.

WALTER E. THAYER.
